UNITED STATES PATENT OFFICE.

WALTER C. CUNNINGHAM, OF PHILADELPHIA, PENNSYLVANIA, ASSIGNOR
TO OPEN TOBACCO PIPE COMPANY, OF NEW JERSEY.

DESIGN FOR A MEMBER FOR TOBACCO-PIPE BOWLS.

SPECIFICATION forming part of Design No. 35,060, dated September 10, 1901.

Application filed August 5, 1901. Serial No. 70,987. Term of patent 7 years.

To all whom it may concern:

Be it known that I, WALTER C. CUNNINGHAM, of Philadelphia, in the State of Pennsylvania, have invented and produced a new and original Design for a Member of a Tobacco-Pipe Bowl, whereof the following is a specification, reference being had to the accompanying drawings.

In said drawings, Figure 1 is an inner face view of a bowl member embodying the essential features of my design. Fig. 2 is a top plan view of said member. Fig. 3 is an edge view of said member.

In said figures said member is shown as comprising a complete annular top A, surrounding the cavity A'. Substantially one-half of the circumference of said top A merges into the outer face A² of the member, which is of curved contour. The remainder of said top A projects abruptly from the substantially flat inner face A³ of the member, into which the cavity A' opens. In the bottom of said cavity A' is a smoke-passage a³, which extends along the neck A⁴ and terminates at

a⁴ in the latter. Between said cavity A' and the bottom perimeter a of the plane face A³ is a septum B. Between the cavity A' and the perimeter a' of the plane face A³ is the septum C.

The material feature of my design consists in the member aforesaid comprising the complete annular top A, which for substantially one-half of its circumference merges into the curved surface A² and for the remainder of its circumference overhangs the substantially flat inner face A³ of said member.

Having described my invention, what I claim as new, and desire to secure by Letters Patent, is—

The design for a member of a tobacco-pipe bowl as herein shown and described.

In testimony whereof I have hereunto signed my name, at Philadelphia, Pennsylvania, this 3d day of August, 1901.

WALTER C. CUNNINGHAM.
